UNITED STATES PATENT OFFICE.

ISAAC L. RIDGE, OF BARTLESVILLE, OKLAHOMA, ASSIGNOR TO RIDGE MANUFACTURING COMPANY, OF BARTLESVILLE, OKLAHOMA, A CORPORATION.

THEFT ALARM FOR AUTOMOBILES.

Application filed February 27, 1924, Serial No. 695,560. Renewed February 17, 1927.

The principal object of this invention is to provide a highly efficient, yet a rather simple and inexpensive alarm which will be actuated in case an automobile equipped therewith, is either driven under its own power, or towed.

A further object of the invention is to provide a support for a casing which contains the alarm mechanism, said support being in the form of a transmission cover plate which is applicable to an ordinary transmission case.

A still further object is to provide attaching means for the above named transmission plate or for the casing, if mounted in another manner, which cannot be released until the alarm is set in an inoperative condition by an authorized person.

Yet another object is to provide the casing with a removable cover or other movable portion for giving access to the casing attaching means, and to provide common locking means for holding said cover or removable portion in locked position, as well as for controlling the operation of the alarm.

A still further aim is to provide a novel form of cam adapted to be easily mounted upon a transmission shaft, between a shaft encircling clutch spring and a relatively stationary shaft-carried member at one end of said spring.

Another aim is to provide a device of the class set forth, so constructed as to make it practically impossible for a thief to throw the same out of operation.

With the foregoing in view, the invention resides in the novel subject matter herein-after described and claimed, the description being supplemented by the accompanying drawings.

Figure 1 is a vertical longitudinal sectional view showing the application of my invention to a transmission mechanism and its usual case.

Figure 2 is a top plan view partly broken away and in horizontal section.

Figure 3 is a view similar to Fig. 1 but partly in elevation illustrating the alarm operating lever in readiness for operation, whereas Fig. 1 discloses this lever locked in an inoperative position, for running the car without operating the alarm.

Figures 4 and 5 are vertical transverse sectional views as indicated by lines 4—4 and 5—5 of Fig. 3.

Figure 6 is a side elevation of the actuating cam for the above-named operating lever.

Figure 7 is a sectional view of the cam as indicated by line 7—7 of Fig. 6.

In the drawings above briefly described, the numeral 1 designates a portion of a well known transmission case which is located below the front floor boards 2 of an automobile, the top of said case being formed with an opening 3 for giving access to transmission parts within. Only a portion of the transmission mechanism has been shown within the case 1, as it is with this portion only that the present disclosure of the invention co-operates. The numeral 4 designates a drive shaft surrounded by the usual clutch collar 5 and clutch spring 6, and provided at its rear end with a stationary member 7 which constitutes one section of the universal joint, by means of which the transmission mechanism is commonly connected with the propeller shaft extending to the rear axle. All of these parts are shown, principally to illustrate the manner in which the present invention co-acts therewith.

At 8, I have shown an inclined transmission cover which is secured by the usual screws 9 to the case 1, to close the opening 3. Extending horizontally from and secured to the lower portion of the cover plate 8, I have illustrated a casing 10 for a suitable bell or other audible alarm 11. In the present disclosure, the casing 10 is provided with a removable cover plate 12 and when this cover plate is in place, a number of the screws 9 are inaccessible, as they are within the casing. Consequently, this casing cannot be removed from the transmission case, without first removing the cover 12, and for reasons set forth below, this is practically impossible when the device is set to sound an alarm, in case the machine is moved by an unauthorized person.

In the preferred construction, the side edges of the cover plate 12 are provided with downwardly extending flanges 13 which embrace the casing 10 and at their front ends may well have inwardly stamped studs 14 engaging sockets 15 in the casing sides, to hold the front end of the cover in place, even when its locking means is released. The rear end of the cover 12 preferably extends under a flange 16 formed on the rear end of the casing 10, and in order to disengage the

cover from said flange, it is necessary to swing its front end upwardly and at the same time slide said cover forwardly. This upward swinging is prevented by the locking means yet to be described, and forward sliding of the cover 12, is prevented, in the present disclosure, by a stationary lock barrel 17 which rises through an opening 20 in said cover, said barrel being suitably mounted, for instance, upon a bracket 21 secured in the casing 10.

Rotatable within the barrel 17, is a well known form of lock cylinder 22, controlled by an appropriate key (not shown) or possibly by permutation locking means. Upon the lower end of the cylinder 22, I have shown a lateral flange 23 adapted to co-act with a keeper 24 on the lower side of the cover plate 12, to hold this cover plate against upward swinging when the alarm mechanism is set for operation, this association being shown in Fig. 3. The lock cylinder 22 controls not only the cover 12, but controls the operation of the alarm mechanism and when operated to hold this mechanism in an inoperative condition, as seen in Fig. 1, the flange 23 is free of the keeper 24 and consequently, the cover plate 12 may be removed, giving access to the previously covered screws 9. Thus, the entire transmission cover plate 8 and parts carried thereby, may be removed for making any necessary repairs to the transmission.

In the construction shown, the cover plate 8 is provided with an opening 25 at its lower or rear end, through which an alarm-operating lever 26 passes, said lever being fulcrumed between its ends at 27 on an appropriate bracket 28 secured to said cover plate 8. Upon the lower end of lever 26, I have shown a roller 29 cooperable with an annular cam 30 which rotates with the shaft 4. This cam is preferably of the angular shape shown in Figs. 1 and 7, in transverse section, so that the inwardly extending flange 31 thereof will be frictionally held between the rear end of the spring 6 and the member 7, while the laterally projecting portion 32 of the cam will surround the rear end of said spring 6. This portion 32 may well be provided with a number of set-screws 33 to bind against the spring 6, thus insuring that there shall be no turning of the shaft 4 without corresponding turning of the cam.

I have shown the upper end of the lever 26 pivotally and slidably connected at 34, with a short lever 35 fulcrumed on a bracket 36 in the casing 10, said lever 35 being linked at 37 to a pivotally mounted alarm actuator 38. Pivoted upon this actuator, a dog 39 has been shown to co-act with a shoulder 40 on a bell clapper 41. A spring 42 is connected with the clapper 41 and another spring 43 is connected with the dog 39. When the cam 30 actuates the lever 26,

this lever in turn swings the lever 35 and causes it to pull upon the link 37, thus swinging the actuator 38 and causing the dog 39 to engage the shoulder 40 and move the clapper 41 outwardly from the gong 11, during which movement the spring 42 is placed under tension. At a predetermined time, the dog 39 disengages the shoulder 40, due to the different arcs upon which the actuator 38 and the clapper 41 swing, and when this takes place, spring 42 swings said clapper forcibly against the gong 11 to sound the latter. This will take place at each operative movement of the lever 26, so that notice is effectively given that the machine is being moved by an unauthorized person. When lever 26 swings toward its vertical position, the actuator 38 is pulled inwardly by the spring 43 and the dog 39 snaps by the shoulder 40 in position to again engage this shoulder, when the actuator 38 is next swung outwardly.

To permit the sound to more easily escape from the casing 10, its sides are by preference formed with openings 44, but guard plates 45 are provided to prevent the insertion of instruments through said openings, in an attempt to throw the alarm out of play.

In order that the lever 26 may be held in a position at which the cam 30 will not actuate the same, I have shown the lower end of the lock cylinder 22 provided with an eccentric stud 46 which co-acts with a lateral extension 47 on the upper end of said lever. Thus, when the cylinder 22 is turned to the proper position, lever 26 will be held as shown in Fig. 1 and the entire alarm mechanism will be held in an inoperative condition to permit running of the machine. When the cylinder is in this position, the flange 23 is free of the keeper 24 and consequently the cover plate 12 of the casing 10 may be removed.

Upon leaving the machine, the operator rotates the lock cylinder 22 to the position disclosed in Fig. 3, thus engaging the flange 23 with the keeper 24 to lock the cover 12 against removal, and at the same time swinging the lever 26 so that it may co-act with the cam 30 to be operated by the latter, if an attempt is made to steal the car, either by running under its own power or by towing.

Excellent results may be obtained from the details disclosed and they are therefore preferably followed, but the present disclosure is principally for illustrative purposes and within the scope of the invention as claimed, numerous changes and modifications may be made.

It may here be stated that by the term "transmission-operated" appearing in certain claims, I contemplate operation of the alarm by any part of an automobile, used

in transmitting power from the motor to the wheels.

I claim:

1. An attachment for automobiles comprising a transmission-operated alarm, and a casing for said alarm having a support in the form of a transmission cover plate provided with openings to receive the usual attaching fasteners, one or more of said openings being accessible only through the casing, the latter having a normally locked movable portion to prevent access to said one or more openings.

2. An automobile attachment comprising an inclined transmission cover plate having an opening at its lower end, a casing extending horizontally from the lower portion of said plate for disposition under the floor of an automobile, an alarm in said casing having an operating member passing through said opening to extend into the transmission case, a cam adapted to be mounted on a rotary transmission part to actuate said alarm, and locking means at the upper side of said casing for moving operating member away from said cam and holding the former.

3. In combination, a transmission case; transmission mechanism in said casing in-

cluding a shaft, a clutch spring surrounding said shaft, and a shaft-carried member at one end of said spring; an annular shaft-encircling cam having a portion held by said spring between the latter and said shaft-carried member, an alarm having an operating member extending into the path of said cam, and locking means for holding said operating member out of the path of said cam.

4. A structure as specified in claim 3; said cam having a portion surrounding one end of said spring and provided with a set screw to engage the latter.

5. An attachment for an automobile transmission casing, comprising an alarm casing, an alarm in said alarm casing, a transmission-controlled alarm-operated member extending into said alarm casing, a removable cover for said alarm casing, a keeper carried by said cover and disposed within said casing, and a rotary locking device co-operative with said cover, said locking device carrying locking means for alternately engaging said keeper and said operating member.

In testimony whereof I have hereunto affixed my signature.

ISAAC L. RIDGE.
